United States Patent Office

Des. 219,953
Patented Feb. 23, 1971

219,953

STUD

Richard B. Ernest, Richboro, Pa., assignor to Penn Engineering & Manufacturing Corp., Danboro, Pa., a corporation of Delaware

Filed Apr. 1, 1970, Ser. No. 22,191

Term of patent 14 years

Int. Cl. D8—04

U.S. Cl. D8—267

FIG. 3

FIG. 2

FIG. 1

FIG. 4

FIG. 1 is a side view of the stud embodying my new design;

FIG. 2 is a bottom, perspective view, thereof, but showing only a part of the shank for convenience of illustration;

FIG. 3 is a top view thereof; and

FIG. 4 is a bottom view thereof.

I claim:

The ornamental design for a stud, as shown and described.
